AMALGAMATOR

William Arthur Grant and Edward Freeman
Roach, Vancouver, British Columbia, Canada

Application September 14, 1937, Serial No. 163,791

4 Claims. (Cl. 209—183)

Our invention relates to improvements in amalgamators. The objects of the invention are to provide means whereby the gold, platinum and other metallic minerals of suitable specific gravity are brought into intimate contact on all sides with the mercury and are immersed therein to the extent that a static pressure equal to the depth of immersion is applied between the wanted particles and the mercury. Further objects are to provide an amalgamator where the mercury is kept entirely clean and oxidation of the mercury is prevented.

The invention consists of a device for forcing metallic mineral bearing liquid pulp downwardly into a body of mercury and effecting a turbulence of the pulp and mercury below the normal mercury level, as will be more fully described in the following specification and shown in the accompanying drawing, in which—

Fig. 1 is a sectional view of the amalgamator.
Fig. 2 is a fractional plan view taken on the line 2—2 of Figure 1.

Fig. 3 is a diagrammatic view showing approximately the flow of pulp and mercury below the liquid level.

In the drawing like characters of reference indicate corresponding parts in each figure.

The numeral 1 indicates a bowl having a peripheral rim 2 over which the tailings flow to a suitable launder 3. The bowl is provided with a bottom outlet 4 through which the mercury is discharged when cleaning out the amalgamator. Standing within the bowl and separated therefrom by legs 5, is an annular block 6 which is preferably of iron for the purpose of weighting the amalgamating plate structure to be herein-after described.

Formed within the annular block 6 is a chamber generally indicated by the numeral 7, having side walls 8 and a bottom wall 9, and concentrically disposed in the chamber 7 is an annular wall 10 forming a well 11 which has its bottom wall in the form of an annular U-shaped groove 12. Extending outwardly from the upper extremities of the wall 8 of the chamber is a plate 13 which is preferably provided with a plurality of apertures 14 and spaced below this plate is a plate 15, which may be integral with the upper surface of the block 6. The plate 13 projects beyond the outer edge of the plate 15 and may be connected to it by supporting pins 16. Extending downwardly from the centre of the plate 13 is a feed pipe 17 having at its upper end a suitable fitting 18 for connection to a pump, not shown, and at its lower end a substantially

frusto conical shroud 19, which shroud serves to direct the pulp towards the upper peripheral rim of the chamber 7. A plurality of orifices 20 are formed along the upper edge of the wall 8 of the chamber 7 and a plurality of openings 21 are formed along the lower edge of said wall.

The total area of the feed pipe 17 and that of the orifices appear to have a definite relation and while good results are obtained with areas of widely varying proportions, best recovery has been hitherto obtained where the areas are such that with a velocity of three discharging into the well from the bottom of the feed pipe 17 the velocity of flow through the orifices 20 equals four.

Mounted above the plate 13 is a dispersing plate 22. The underside of the dispersing plate slopes radially upwards towards its periphery as at 23, so that the lighter particles of material rising into contact with it will move radially outward and impress their metallic content upon its amalgam coated surface.

Surrounding the rim 2 of the bowl 1 we provide an annular channel 24 which is adapted to receive any small globules of mercury that pass out from the bowl and substantially fitting said channel is a flat copper ring 25 which floats on the accumulated mercury. The upper level of the channel 24 is some distance below the rim. Surrounding the channel 24 is an annular flange 30 of copper 26 which is relatively flat and has its outer edge directly over the launder 3.

All the parts below the mercury level X and in contact with the mercury level are of copper or are coated with copper or other metal having an affinity for mercury and the pulp contacting surfaces of the bowl 1, the dispersing plate 22 and the channel 24 as at Z are of iron or other material to which mercury will not adhere, so as to prevent the mercury from creeping beyond its useful zone to facilitate the precipitation of any mercury globules which may be in suspension in the water flowing upwards above the normal mercury level X.

In operating the device, the bowl is filled with mercury to the line X and liquid pulp is pumped through the feed pipe 17 into the well 11 against the static pressure of the mercury therein, the ore content and water will be forced upwards in a state of fine division due to the mercury pressure and the larger particles of gold will be immediately encased in mercury, so that their amalgamation with the mercury may commence, platinum and other metallic minerals of great specific gravity which cannot be amalgamated

will lag and precipitate into the mercury. The lighter particles of gold, black sand and other unwanted material will be carried upwards at an increasing rate of speed past the frusto conical portion 19 and be projected through the orifices 20 and between the plates 15 and 13 into the space or zone Y where the velocity attained in passing through the orifices 20 will be rapidly reduced. The outward flow of pulp and mercury through the zone Y from each of the orifices will cause back eddies, causing ore laden water globules to be scrubbed with mercury and as some ore laden globules escape upwards through the apertures 14 globules of mercury will descend through said apertures to enter the radial stream. Such particles of gold which are not immediately entrapped in the body of the mercury are worked by the flow through the zone Y onto the silvered surfaces of the plates 15 and 13, any values passing upwards through the orifices 14 will impinge upon the sloping surface 23 of the dispersing plate 22 and unwanted material will creep along said surface to the periphery of the plate and will then rise above the mercury level X and be carried over the rim 2 across the channel 24 and the flange 26 to discharge into the launder 3. Any globules of mercury carried over the rim will impinge on the flat ring 25, which being solid, will cause them to break up and either adhere to said ring or creep down into the channel 24, the tailings flowing from the channel onto the flange 26 will due to the decreasing water flow and reduction of stream depth, cause any remaining mercury to be entrapped.

Mercury flowing beyond the peripheral edge of the plate 15 will circulate in the bowl and return to the chamber where it will again rise and intermix with the incoming pulp from the feed pipe 17. The rise of the mercury between the wall 10 of the well 11 and the wall 8 of the chamber 7 is accelerated by the difference in specific gravity of the liquid above it due to the presence of water and that of the water free column of mercury between the periphery of the block 6 and the bowl 1.

What we claim as our invention is:

1. An amalgamator comprising a mercury bowl, a pulp feed pipe adapted to discharge below the mercury level in the bowl, a chamber within the bowl having vertical side walls and top and bottom walls, a cup mounted on the bottom wall, said cup surrounding the discharge end of the feed pipe, a pair of spaced horizontal plates

adjacent the top and surrounding the chamber, said chamber walls having an orifice adjacent to the plates and communicating therebetween and an orifice adjacent the bottom wall and in communication with the base of the mercury bowl. 5

2. An amalgamator comprising a mercury bowl, a pulp feed pipe adapted to discharge below the mercury level in the bowl, a chamber within the bowl having vertical side walls and top and bottom walls, a cup mounted on the bottom wall, said cup surrounding the discharge end of the feed pipe, a pair of spaced horizontal plates adjacent the top and surrounding the chamber, said chamber walls having an orifice adjacent to the plates and communicating therebetween and an orifice adjacent the bottom wall and in communication with the base of the mercury bowl, said plates consisting of upper and lower plates and said upper plate extending beyond the lower plate. 10

3. An amalgamator comprising a mercury bowl, a pulp feed pipe adapted to discharge below the mercury level in the bowl, a chamber within the bowl having vertical side walls and top and bottom walls, a cup mounted on the bottom wall, 25 said cup surrounding the discharge end of the feed pipe, a pair of spaced horizontal plates adjacent the top and surrounding the chamber, said chamber walls having an orifice adjacent to the plates and communicating therebetween and an orifice adjacent the bottom wall and in communication with the base of the mercury bowl, said horizontal plates serving to define a lateral flow zone for the pulp and entrained mercury. 30

4. An amalgamator comprising a mercury bowl, a pulp feed pipe adapted to discharge below the mercury level in the bowl, a chamber within the bowl having vertical side walls and top and bottom walls, a cup mounted on the bottom wall, said cup surrounding the discharge end of the feed pipe, a pair of spaced horizontal plates adjacent the top and surrounding the chamber, 40 said chamber walls having an orifice adjacent to the plates and communicating therebetween and an orifice adjacent the bottom wall and in communication with the base of the mercury bowl, and a dispersing plate disposed above the horizontal plates, said dispersing plate having a sloping undersurface, said undersurface being inclined in the direction of flow of pulp within the 45 bowl. 50
